DISH BRUSH

Per Lindbo, Oslo, Norway, assignor to A/S W. Jordan
Børste & Pensel fabrik, Oslo, Norway

Filed Nov. 20, 1972, Ser. No. 308,296

Claims priority, application Norway Sept. 4, 1972

Term of patent 14 years

Int. Cl. D4—01

U.S. Cl. D4—31

FIG. 1 is a perspective view of the top of a dish brush showing my new design;

FIG. 2 is an elevational view of the side of said dish brush looking from the left in FIG. 1;

FIG. 3 is an elevational view of the bottom of said dish brush; and

FIG. 4 is an elevational view of the end of said dish brush looking upwardly in FIG. 3.

The opposite side of FIG. 2 is identical with the side shown.

I claim:

The ornamental design for a dish brush, as shown and described.
